UNITED STATES PATENT OFFICE

2,265,391

ARTIFICIAL TOOTH

Simon Myerson, Brookline, Mass

Application April 27, 1938, Serial No. 204,512

1 Claim. (Cl. 32—10)

This invention relates to improvements in artificial teeth and backings therefor.

The purpose of the invention is to provide an artificial tooth having a gingival contact of porcelain, and also an occlusal or biting portion of porcelain. By the construction of my tooth and backing I have provided an extremely strong and easily workable porcelain member and backing member having, in addition, the advantages of wide range of application in the restoration of lost teeth as well as preserving a highly aesthetic appearance.

For convenience of description I shall designate the porcelain or the like member as a tooth; and the metallic or like member as the backing; and that portion of the tooth to which the backing is to be fitted as the body portion; and the remainder of the tooth as the crown portion. It follows as a matter of course then that the gingival portion is part of the body and the occlusal portion is part of the crown.

I will now proceed to describe my invention and its use, referring to the accompanying drawing in which corresponding and like parts are designated throughout the several views by the same reference characters.

Fig. 1 is a side view of a posterior tooth made in accordance with my invention;

Fig. 2 is a buccal view of such a tooth;

Fig. 3 is a lingual view of such a tooth;

Fig. 4 is a perspective view of one type of backing to be used with a tooth shown in the preceding figures;

Fig. 5 is a perspective view of an optional backing;

Fig. 6 is a side view of the assembled tooth and backing, after the backing has been completed as herein described;

Fig. 7 is a buccal view of a bridge in the mandible extending from the first molar to the cuspid, this bridge carrying two bicuspid dummies made in accordance with this invention;

Fig. 8 is a top view of the bridge shown in Fig. 7;

Figs. 9, 10 and 11 are sections respectively on lines 9—9, 10—10 and 11—11 of Fig. 2;

Figs. 12 and 13 are sections on lines 12—12 and 13—13 respectively of Fig. 6;

Fig. 14 is a side view of an anterior tooth; and

Fig. 15 is a perspective view of a backing therefor.

As shown particularly in Figs. 1, 2 and 3, an artificial tooth formed in accordance with this invention may be provided with a smooth body or base 1, which tapers slightly from its upper or

occlusal end downwardly toward its gingival portion 5 on all of its faces. This tooth is provided with a crown 9 having a buccal face 2 and a lingual face 3; the upper part of the crown obviously provides the occlusal face 4 of the tooth. At each side of the tooth, the recessed base portion or body portion may be provided with an extension 6 which may extend to the occlusal face, thus separating the buccal portion 2 and the lingual portion 3 of the crown, these portions of the crown being offset relative to the base and its extensions 6. The crown portion 2 is thus provided with a shoulder or margin 7, while the crown portion 3 is provided with a similar shoulder 7^a. These shoulders, as shown in Figs. 1, 2 and 3, may extend downwardly from the occlusal face 4 of the tooth. Thus the shoulder 7 may extend downwardly along the mesial portion of the tooth toward the gingival portion across the buccal face and to the occlusal surface on the distal aspect of the tooth. The margin or shoulder 7^a may extend from the occlusal face of the tooth on its mesial aspect toward the gingival portion of the tooth and across the lingual face to the occlusal surface on the distal aspect of the tooth. If desired, the shoulders may be slightly undercut. It is evident that the crown portions 2 and 3 provide surfaces which are continuous with the occlusal surface 4 of the tooth.

Fig. 1 is a side view of a posterior tooth made in accordance with my invention;

Fig. 2 is a buccal view of such a tooth;

Fig. 3 is a lingual view of such a tooth;

Fig. 4 is a perspective view of one type of backing to be used with a tooth shown in the preceding figures;

Fig. 5 is a perspective view of an optional backing;

Fig. 6 is a side view of the assembled tooth and backing, after the backing has been completed as herein described;

Fig. 7 is a buccal view of a bridge in the mandible extending from the first molar to the cuspid, this bridge carrying two bicuspid dummies made in accordance with this invention;

Fig. 8 is a top view of the bridge shown in Fig. 7;

Figs. 9, 10 and 11 are sections respectively on lines 9—9, 10—10 and 11—11 of Fig. 2;

Figs. 12 and 13 are sections on lines 12—12 and 13—13 respectively of Fig. 6;

Fig. 14 is a side view of an anterior tooth; and

Fig. 15 is a perspective view of a backing therefor.

As shown particularly in Figs. 1, 2 and 3, an artificial tooth formed in accordance with this invention may be provided with a smooth body or base 1, which tapers slightly from its upper or

occlusal end downwardly toward its gingival portion 5 on all of its faces. This tooth is provided with a crown 9 having a buccal face 2 and a lingual face 3; the upper part of the crown obviously provides the occlusal face 4 of the tooth. At each side of the tooth, the recessed base portion or body portion may be provided with an extension 6 which may extend to the occlusal face, thus separating the buccal portion 2 and the lingual portion 3 of the crown, these portions of the crown being offset relative to the base and its extensions 6. The crown portion 2 is thus provided with a shoulder or margin 7, while the crown portion 3 is provided with a similar shoulder 7^a. These shoulders, as shown in Figs. 1, 2 and 3, may extend downwardly from the occlusal face 4 of the tooth. Thus the shoulder 7 may extend downwardly along the mesial portion of the tooth toward the gingival portion across the buccal face and to the occlusal surface on the distal aspect of the tooth. The margin or shoulder 7^a may extend from the occlusal face of the tooth on its mesial aspect toward the gingival portion of the tooth and across the lingual face to the occlusal surface on the distal aspect of the tooth. If desired, the shoulders may be slightly undercut. It is evident that the crown portions 2 and 3 provide surfaces which are continuous with the occlusal surface 4 of the tooth.

Fig. 5 illustrates an optional form of backing 10 with buccal and lingual aspects 11^a and 12^a respectively and with extensions 13^a. In general this backing is similar to that shown in Fig. 4, but the flanges 14 and 14^a are omitted, and relatively thick upper edges 13 and 13^a are provided to engage the shoulders 7 and 7^a respectively of a tooth.

Fig. 6 shows the manner in which a backing of the type shown in Fig. 4 may be assembled

with a tooth of the type shown in Figs. 1, 2 and 3. In this figure the buccal and lingual portions of the backing are shown in dotted lines and are designated respectively by numerals 11 and 12. As shown, a body of solder 18 may be disposed beneath and between the flanges 14 and 14^a; rather than solder, casting gold or other material may be employed to complete the backing. The lower, exposed portion of the body is designated by the numeral 19 in this figure.

Figs. 7 and 8 show natural teeth 20 and 21, namely, a first molar and a cuspid used as abutments to carry the artificial teeth 22 and 23. Inlays 24 and 25 are shown in dotted lines in Fig. 7, being soldered or otherwise joined to the backings. The exposed gingival portions of the bases of the teeth are designated by the numerals 19 in Fig. 7 and the exposed buccal portions of the crowns of these teeth by the numeral 9. As shown in Fig. 8, solder 18^a or the like may be employed to join the extensions 13 of the backings.

In Fig. 14, corresponding reference numerals designate parts similar to those shown in Fig. 1, except that the incisal portion of the anterior tooth is designated by reference character 4^b.

Fig. 15 shows a backing 16^b which may be employed with such a tooth and which is provided with a buccal aspect 11^b and a lingual aspect 12^b, as well as extension 13^b.

In practice, I use a molar or bicuspид tooth, as shown for example in Fig. 1, and a thin backing such as is represented in Fig. 4, which has been made to closely fit the porcelain tooth body. In the manufacture of my tooth in porcelain, it is readily feasible to control the size of the tooth to fairly constant dimensions with occasional maximum variations of from .005 to .010 of an inch. Moreover, the backing may be slit at any point so that it may be taken up to fit the tooth if loose, or if it be tight it can be readily stretched by light tapping with a hammer, or be burnished, as preferred. I prefer to use the closed backing as illustrated in the figures, as the slight stretching, where necessary, is so easily accomplished.

In selecting teeth for the case, I select teeth that go freely into their places and which require a minimum of gingival and occlusal grinding. Having fitted the teeth into their position, I then burnish the backing and the flanges (if the flange type of backing is used) and the extending portions to fit the body and shoulders and the crown margins. Then I swage the backing to the tooth and then complete the backing by waxing to the proper contours, thereafter removing the tooth from its backing, the investing and casting being done in the usual manner.

It will be seen that the backing forms a strong and rigid encasement for the tooth body and that the extensions provide convenient and properly located means for joining the backing members of the teeth to any type of abutment or to other backing members and that the extensions of the backing form valuable reinforcement to the rest of the backing in resistance to strong lingual-buccal forces of mastication; and that they also provide the utmost mechanical advantage against these forces because the juncture can take place close to, if not exactly at the same level at which the forces are applied.

Also, this construction provides a hygienic advantage in that the juncture may be made as far as necessary from the gum tissue and makes

it possible to finish the mesial and distal surfaces to clean, smooth gingival edges.

It is also possible to make a rigid backing of sufficient thickness (Fig. 5) so that its upper edges may be flush with the crown margins 7 and 7^a, thereby making it unnecessary to use any filler or solder except for the purpose of joining the members of the bridge or denture. Also, it is possible to combine a soft pliable backing with 10 a more rigid one, as follows: Adapt the pliable backing in the manner already described, set upon this backing a rigid backing, leaving margins of the pliable backing exposed, remove, and solder the two together.

In making a bridge or denture with my dummies, any type of abutments may be used, including removable types. In the bridge which I have chosen for illustration, inlay abutments have been used. The inlay abutments are fitted to place and a wax bite is taken with the jaws in proper full centric occlusion. After this an impression is taken; the abutments should come off with the impression or be placed in the impression should this be necessary. Articulated models should be poured in the usual manner. The individual dummies should each be separately fitted and completed, then fixed in place with wax. The teeth should be oiled before being fixed in place upon the model, so that the wax will stick to the backings and not to the teeth. The teeth should then be removed from the backings and the bridge invested and completed by soldering the members together as is customary in the art. If the gingival surfaces of the teeth have been ground, they should be re-glazed before they are cemented to their backings.

The completed bridge will be seen to have many advantages over the prior art. The porcelain members only of the dummies contact the gingiva. Each individual dummy can be finished to smooth and natural contours and be free from food-retaining pockets. The gold or other metal members are freely accessible to cleaning with a tooth brush or other means, and can quite readily be kept clean. The construction secures the maximum strength for the amount of metal used and also the maximum strength in the porcelain tooth, the porcelain tooth also having an exposed occlusal of porcelain. It will be seen that lower molars and bicuspids as well as anteriors, made after my invention, will show very little metal, that part of the backing which crosses the buccal or labial aspects of the tooth being entirely invisible in lower bridges. In upper teeth this is not true in all cases, especially with relation to the anterior teeth, as some people expose their anterior teeth much more than others do. The advantages gained, however, more than offset this possibility. In cases where it is indicated, one may use a metal of less conspicuous color than the gold alloys ordinarily used.

Although I have not shown a molar dummy in the illustrations, it is obvious that the construction might be similar to that illustrated, in all the figures except Fig. 14.

It should be understood that the present disclosure is for the purpose of illustration only and that this invention includes all modifications and equivalents which fall within the scope of the appended claim.

I claim:

A backing for an artificial tooth comprising 75 an annular lower portion for substantially en-

tirely encircling the base of a tooth, said backing having a lower edge to conform to the gingival portion of a tooth, said backing having extensions to project substantially to the occlusal surface of the tooth at the mesial and distal sides thereof, the backing being provided with a flange extending along the front edge of one of said extensions and along the upper edge of the buccal portion of the backing and thence along the

5 front edge of the opposite extension, the backing having a second flange extending along the rear edge of one extension, along the upper edge of the lingual portion of the backing, and then along the rear edge of the other extension, the buccal portion of the backing having a smaller depth than its lingual portion.

SIMON MYERSON.
